SEAT CUSHION

William M. Emery, 44 Pittsford Way,
New Providence, N.J.

Filed Mar. 8, 1965, Ser. No. 84,124

Term of patent 14 years

(Cl. D3—9)

FIG. 1

FIG. 2

FIG. 3

FIGURE 1 is a plan view of a seat cushion, showing my new design;

FIGURE 2 is an edge view looking from the bottom of FIGURE 1; and

FIGURE 3 is an edge view looking from the side of FIGURE 1.

The face not shown is substantially the same as the face shown in FIGURE 1.

The edge opposite to that shown is substantially the same as the edge shown in FIGURE 2.

The edge opposite to that shown is substantially the same as the edge shown in FIGURE 3.

I claim:

The ornamental design for a seat cushion, as shown and described.
